UNITED STATES PATENT OFFICE.

EVERETT E. LUNDBERG, OF DETROIT, MICHIGAN, ASSIGNOR TO BRIGGS MANUFACTURING COMPANY, OF DETROIT, MICHIGAN, A CORPORATION OF MICHIGAN.

ADJUSTABLE DOVETAIL CONSTRUCTION.

Application filed November 2, 1925. Serial No. 66,328.

This invention relates generally to dovetail constructions, particularly designed for use with the doors of vehicle bodies and the like.

5 One of the essential objects of the invention is to provide a simple form of dovetail that is adjustable without interfering with the usual trimming material of the vehicle body to compensate for any irregularities 10 such as sagging resulting from the mounting of the door; to prevent rattling and to take care of wear of the engaged parts while in use.

Another object is to provide a dovetail of 15 this type that can be manufactured and assembled at a comparatively low cost.

With the above and other objects in view, the invention resides in certain novel features of construction, combinations and arrangements of parts as will be more fully pointed out in the appended claims.

In the accompanying drawing:

Figure 1 is a fragmentary side elevation of a door pillar with a dovetail member embodying my invention attached thereto.

Figure 2 is a vertical sectional view taken on the line 2—2 of Figure 1.

Figure 3 is a cross sectional view taken on the line 3—3 of Figure 2.

30 Referring now to the drawing, the numeral 1 designates a door pillar having a depressed portion 2 in the outer wall 3 thereof for receiving the dovetail member 4. As shown, this member 4 has a flat base 5 and the laterally projecting horizontally disposed tongue 6 that is adapted to engage a suitable keeper (not shown) on the door jamb when the door is closed.

In order that the dovetail will compensate 40 for irregularities such as sagging, resulting from mounting the door and also for wear of the engaged parts, the member 4 is preferably adjustable longitudinally of the vertical door pillar 1. As shown, spaced elongated slots 7 are provided in the depressed portion 2 of the pillar for receiving suitable securing elements such as the screws 8 which extend freely through the base 5 of the dovetail member and threadedly engage a flat attaching plate 9 located on the inner side of the pillar 1. Thus, with this construction, the dovetail member 4 and plate 9 are capable of moving as a unit longitudinally of the pillar to the proper position, whereupon

the screws 8 may be adjusted to clamp the 55 base 5 and plate 9 firmly against opposite sides of the depressed portion 2.

To prevent any accidental displacement of the dovetail member 4 when in adjusted position, the base 5 of said member is preferably provided with suitable transversely extending serrations 10 which are engageable with similar serrations 11 on the adjacent outer face of the depressed portion 2 of the door pillar.

Located upon the inner face of the depressed portion 2 of the pillar is a sheet metal housing 12 for the attaching plate 9. As shown, this housing 12 is preferably a closed channel having the lateral flanges 13 and 14 respectively which are preferably welded to the adjacent portions of the pillar. Thus, with this construction, the attaching plate 9 will always be held in rear of the depressed portion 2, hence the screws 8 may be loosened or removed entirely to adjust or replace the dovetail member without losing the attaching plate 9 and may subsequently be readily adjusted in the attaching plate to hold the dove tail member. As a result of this construction it will not be necessary to remove or replace any of the usual trimming material to gain access to the inner side of the pillar for the purpose of holding the attaching plate during any of the operations mentioned above.

While it is believed that from the foregoing description, the nature and advantage of my invention will be readily apparent, I desire to have it understood that I do not limit myself to what is herein shown and described and that such changes may be resorted to when desired as fall within the scope of what is claimed.

What I claim as my invention is:

1. The combination with a door pillar having a depressed portion, in a wall thereof, of a dovetail member in said depressed portion and an adjustable connection between said member and pillar permitting said member to be adjusted lengthwise of said pillar without being removed therefrom.

2. The combination with a door pillar having a depression therein, of a dovetail member having a flat base seated in said depression, an attaching plate on the back of said depression, and securing means for the

dovetail member extending freely through the base, movable lengthwise of the depression and threadedly engaging said plate.

3. In combination, a dovetail having a substantially flat base and a laterally projecting tongue disposed at substantially right angles to the base, an attaching plate substantially parallel to the base, adjustable securing elements for the dovetail extending freely through the base and threadedly engaging said plate, and a supporting member disposed between the dovetail and plate and having elongated slots receiving the securing elements aforesaid, the connection between said dovetail, supporting member and plate being such that the dovetail and attaching plate may be adjusted as a unit upon the support without being removed from said supporting member and without interfering with any other part that may be associated with said support.
4. In combination, an upright member having a substantially flat portion provided with an elongated longitudinally extending slot, a dovetail having a base upon the outer side of said flat portion and having a later-

ally projecting tongue disposed at substantially right angles to said base, an attaching plate upon the inner side of said flat portion, and an adjustable connection between said base and plate including an element extending freely through said base and slot and threadedly engaging said plate.

5. The combination with a pillar having an upright metal wall, of a dovetail assembly carried thereby and adjustable as a unit relative thereto without being removed therefrom, said assembly including a dovetail member upon one side of said wall, a member upon the opposite side of said wall, and an adjustable connection between said first and second mentioned members normally holding said assembly in position upon said wall but adapted upon being adjusted to permit said assembly to be bodily adjusted relative to said wall as aforesaid, said connection including an element extending freely through one of said members and threadedly engaging the other of said members.

In testimony whereof I affix my signature.

EVERETT E. LUNDBERG.
